BICYCLE SADDLE BAG

Melbert A. Kline, 1157 Silverdale,
Wichita, Kans. 67218

Filed Oct. 16, 1974, Ser. No. 515,240

Term of patent 14 years

Int. Cl. D12—11

U.S. Cl. D12—158

FIG. 1 is a side elevational view of a bicycle saddle bag showing my new design, the opposite side being a mirror image thereof;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a bicycle saddle bag, substantially as shown.
